UNITED STATES PATENT OFFICE.

WILLIAM COURTNEY PIGGOTT, OF LONDON, ENGLAND.

WHEEL-GUARD.

1,088,618.

Specification of Letters Patent. Patented Feb. 24, 1914.

Application filed December 14, 1912. Serial No. 736,839.

To all whom it may concern:

Be it known that I, WILLIAM COURTNEY PIGGOTT, a subject of the King of Great Britain and Ireland, and a resident of London, England, have invented certain new and useful Improvements in Wheel-Guards; and I do hereby declare the following to be a full, clear, and exact description of the same.

10 This invention relates to improvements in life-guards for the road wheels of motor cars and other self propelled vehicles.

15 The guard comprises a depending guard member in the form of a leaf spring mounted in front of the front or back road wheel above the road surface, with facility of rearward, upward and preferably lateral movements, on the front wheel stub or movable axle or other part of the vehicle so that 20 the guard member will, under normal conditions, remain in front of its wheel.

25 In the operation of the device, when the guard member collides with a fallen person, it prevents the wheel from passing over him, and when the guard member collides with an immovable object, such as a curb or irregularity of the road surface, the guard member yields rearwardly, or upwardly, or laterally, by reason of its construction and 30 method of mounting, so that no damage is done.

35 The invention is illustrated in the accompanying drawings, as applied by way of example, to the chassis of a motor omnibus, and its application to other vehicles will be obvious therefrom.

40 Figure 1 is a side elevation taken at the front end of the chassis, the suspension springs being omitted and showing the guard member mounted in front of the front road wheel; Fig. 2 is a front elevation partly in section of the parts shown in Fig. 1; Fig. 41 is a plan; Fig. 4 is a sectional elevation on an enlarged scale showing the guard member mounted with facility of lateral movement; Fig. 5 is a side elevation, partly in section, of a modification showing the guard member mounted in front of the front road wheel; Fig. 6 is a perspective view of 45 the parts shown in Fig. 5; and Fig. 7 is a sectional elevation on an enlarged scale showing the guard member slidably mounted in a socket or guide.

46 *a* represents the frame of the vehicle; *a'* 50 the suspension springs; *b* the front wheel stub or movable axle movable around the

vertical pin, *b'*, supported by the front wheel stationary axle, *b''*, in customary manner; and *c* the front wheel.

47 *d* represents a depending guard member which is made in the form of a leaf spring, and is mounted at the front end of an arm or lever, *d'*, which may be adapted to turn up or down on a pivot, *d''*, on a bracket or carrier, *e*, clamped or otherwise made fast, 55 for example, to the front wheel stub or movable axle, *b*. The arm is preferably provided with and adjustably supported by a setscrew, *f*, bearing against a stop, *e'*, preferably on the bracket, and is normally retained in its lowest position by a spring, *g*, connected to the arm at *g'*, and to the bracket at *g''*. The spring *g* is secured by its ends being formed with eyes which encircle cross bolts on the arm as shown at *g'* and *g''* 60 aforesaid. The spring operates by bearing at its center part against the pivot *d''* and tending to bring its forward end downward. The guard member is mounted in a socket, *d''*, on the arm, by means of a pivot, 65 *h*, so as to have facility of limited lateral movement, and is normally held directly in front of the wheel by a spring, *i*, connected to the guard at *i'*, and to the arm, *d'*, at *i''*. The head of the guard member is specially 70 shaped, as shown in Fig. 4 to accommodate and limit the lateral movement.

75 In the modification represented in Figs. 5, 6 and 7, the head of the guard member, *d*, is mounted as a slide in a vertical or approximately vertical socket or guide, *d''*, integral with the bracket, or carrier, *e*, to provide for up and down movement, and a spring or springs, *f*, is or are provided to resiliently keep the guard member, *d*, in its 80 lowest or normal position above the ground, the guard members, *d*, being provided with stops, *d''*, adapted to engage abutments, *d''*, on the guide. In this case, the lateral movement of the guard member is provided for 85 by its own resiliency. The guard member may be provided with rollers or small wheels, *d''*, at its lower end, and with a pad or cushion, *d''*.

90 What I claim as my invention and desire to secure by Letters Patent is:—

95 1. In a vehicle wheel life guard, in combination, a carrier mounted so as to partake of steering movements of said wheel, a member adapted to rise and fall in relation to 100 said carrier, spring means for normally retaining said member in its lowest position,

and a guard member in the form of a leaf spring depending in front of the wheel and connected at its upper end to said first-mentioned member, substantially as described.

- 5 2. In a vehicle wheel life guard, in combination, a carrier mounted so as to partake of steering movements of said wheel, a forwardly extending lever pivoted at its rear end to said carrier with facility of rising 10 and falling movements, a guard member in the form of a depending leaf spring pivotally connected at its upper end to the forward end of said lever so as to have facility of lateral movement, and spring means for 15 normally retaining said guard member in front of the wheel, substantially as described.
3. In a vehicle wheel life guard, in combination, a member extending at the side 20 and in front of said wheel and mounted so as to partake of steering movements thereof, a socket at the forward end of said member, a guard member in the form of a leaf spring depending from and pivotally 25 mounted in said socket with facility of limited lateral movement, and spring means for normally retaining said guard member in position in front of the wheel, substantially as described.
- 30 4. In a vehicle wheel life guard, in combination, a carrier mounted so as to partake of steering movements of said wheel, a for-

wardly extending lever pivoted at its rear end to said carrier with facility of rising and falling movements, spring means for 35 normally retaining said lever in its lowest position, a set screw and stop for adjusting the downward movement of said lever, and a guard member in the form of a depending leaf spring connected at its upper end to the 40 forward end of said lever, substantially as described.

5. In a vehicle wheel life guard, in combination, a carrier mounted so as to partake of steering movements of said wheel, a forwardly extending lever pivoted at its rear end to said carrier with facility of rising and falling movements, spring means for 45 normally retaining said lever in its lowest position, a set screw and stop for adjusting 50 the downward movement of said lever, a guard member in the form of a depending leaf spring pivotally connected at its upper end to the forward end of said lever so as to have facility of lateral movement, and 55 spring means for normally retaining said guard member in front of the wheel, substantially as described.

In testimony whereof I affix my signature, in presence of two subscribing witnesses. 60

WILLIAM COURTNEY PIGGOTT.
